UNITED STATES PATENT OFFICE.

PAUL L. CHARBONNIER, OF BOSTON, MASSACHUSETTS.

SCRIBING INSTRUMENT.

1,126,390.

Specification of Letters Patent.

Patented Jan. 26, 1915.

Application filed January 31, 1914. Serial No. 815,821.

To all whom it may concern:

Be it known that I, PAUL L. CHARBONNIER, a citizen of the French Republic, residing at Boston, in the county of Suffolk and State of Massachusetts, have invented new and useful Improvements in Scribing Instruments, of which the following is a specification.

This invention relates to improvements in scribing instruments and has for its object to provide a strong, compact device by means of which circles and arcs of various radii may be described, during which operation the centering member and the scribing member may at all times be maintained parallel to each other, whereby when a pen is used as the scribing member both points of said pen will engage the surface upon which said circles or arcs are being described irrespective of the diameters or radii thereof.

The object of the invention is further to provide means whereby said centering and said scribing members may be moved to predetermined distances apart and clamped in said positions.

The object of the invention is still further to provide a handle whereby said instrument may be revolved about the centering member, said handle being at all times maintained with its median axial line parallel with the centering and scribing members.

The object of the invention is still further to provide means adapted to limit the outward movements of said centering and scribing members relatively to each other.

The object of the invention is still further to provide an instrument in which the centering and scribing members may be readily detached from the legs thereof and replaced by other members.

The invention consists in the combination and arrangement of parts whereby the above objects and certain other objects hereinafter appearing may be attained, as set forth in the following specification and particularly pointed out in the claims.

Referring to the drawings: Figure 1 is a side elevation, partly in section, of a scribing instrument embodying my invention with the legs of said instrument shown separated a substantial distance apart in full lines, while the dotted lines illustrate other positions of said legs. Fig. 2 is a section partly in elevation of the instrument illustrated in Fig. 1 and taken on the line 2-2

of said figure. Fig. 3 is a front elevation of the instrument with the legs thereof shown in their closed position. Fig. 4 is a detail sectional view of the head of a modified form of a scribing instrument.

Like numerals refer to like parts throughout the several views of the drawings.

In the drawings, 5 is a centering member preferably provided with a detachable and reversible needle 6 and 7 is a scribing member, which may have formed or attached at its end any suitable scribing instrument, a pen 8 being shown to better illustrate the advantages of the instrument.

The members 5 and 7 are arranged parallel to each other and means are provided by which said members may at all times be maintained in such relation. The preferred means for accomplishing this feature of the invention preferably consists of a pair of legs 9 and 10 pivotally connected together at their upper ends 11, while at their lower ends said legs are pivotally connected at 12 and 13 to the centering member and the scribing member respectively, which pivots are arranged substantially midway of the ends of said members 5 and 7 respectively.

In addition to the legs 9 and 10 a pair of links 14 and 15 are provided, these links being pivotally connected together at their upper ends by a pin 16, while the free ends 17 thereof are slidably connected to the members 5 and 7 respectively. The legs 9 and 10 are preferably bifurcated to receive the links 14 and 15 respectively, which links are pivoted at 18 to the furcations of said legs. It will be obvious in view of the arrangement of said links and their pivots that by moving the members 5 and 7 toward or from each other, the links 14 and 15 will be rocked upon their pivots 18 and the ends 17 of said links will be moved toward and from the pivots for their respective members, namely 12 and 13, and in a direction parallel to the median axial lines of said members.

On certain occasions it is desirable to set the centering member and the scribing member at predetermined distances apart, thus serving as a trammel or a beam compass. To accomplish this feature of the invention, the members 5 and 7 are each provided with a slot 19 which extends substantially from the pivots 12 or 13 to the end 20 of said members, while to the ends 17 of each of the links 14 and 15 is secured a screw 21 which is

adapted to enter and substantially fit the slot 19 and to reciprocate longitudinally therein. The screw 21 is screw-threaded at its outer end and adapted to receive a nut 22 which may be rotated on said screw to bind or clamp the ends 17 at the point desired relatively to the members 5 and 7, the clamping of one of said members sufficing to secure the legs at the required distance.

10 It is often desirable to remove the members 5 and 7 from the instrument and replace the same by pencils or needle points, this being especially the case in connection with the member 7. To save time in such an 15 operation the members 5 and 7 are each provided with an opening 23 in one side thereof, preferably the outer side, which communicates with the slot 19, said opening being of a sufficient size to permit the screw 21 to be 20 inserted or removed therethrough, which may be readily accomplished by spreading the members 5 and 7 until said screws 21 aline with said openings, whereupon the member 5 or the member 7, as desired, may 25 be rotated upon their respective pivots 12 and 13 until free from said screws, thus permitting said members to be removed from said pivots.

A handle 24 is provided for said instrument, said handle being pivotally arranged 30 relatively to the axis common to the legs 9 and 10 of said instrument, this result being preferably accomplished by providing a pair of ears 25 and 26 at the upper end of one 35 of the legs, preferably the leg 9, said ears each having a center screw 27 arranged therein with the points of said screws turned inwardly, one of which is adapted to engage a recess 28 in a portion 29 of the handle 24, 40 said portion being cylindrically formed and adapted to conform with the ears 25 and 26, which are of like formation, and the cylindrical portion 30 of the leg 10 of said instrument which is interposed between the 45 portion 29 of the handle 24 and the ear 25 of the leg 9. The screw 27 mounted in said ear 25 engages a recess 31 in said member 30. Upon the periphery of the cylindrical portion 29 of said handle are formed stops 32 50 and 33 adapted to be engaged by like projections 34 and 35 formed upon the legs 9 and 10 respectively, said stops being for the purpose of limiting the outward pivotal movements of said legs. Means are also 55 provided to maintain the median axial line of said handle parallel with said centering and scribing members, which means preferably consists of a rod 36 arranged to slide in said handle. Said rod has formed at its 60 lower end a disk 37 conforming in shape to the upper ends of the links 14 and 15, said disk being arranged between said ends and adapted to be held in engagement therewith by the pin 16, which is slightly upset at its 65 opposite end to retain the same in place and

the links in contact with said disk. The combined thickness of the ends of said links 14 and 15 of said disk are equal to the slots 38 in the legs 9 and 10, which result in said members being bifurcated, said slots 70 being adapted to receive said links when the legs 9 and 10 are moved to their closed position, as illustrated in Fig. 3.

In Fig. 4 I have illustrated a modified form of the instrument in which means are 75 shown for the purpose of adjusting the moving members 5 and 7 toward and from each other, said means also being adapted to maintain said members at the desired distance apart. This means consists of a screw-threaded rod 39 having a disk 40 formed at its lower end between the links 14' and 15' and adapted to swivel about the common axis of said links, said rod adapted to slide in a handle 24' as in Fig. 1. A recess 41 is 80 arranged transversely of said handle within which is disposed a nut 42 having screw-threaded engagement with said rod 39 and upon rotation thereof causes said rod to be moved longitudinally of said handle to draw 85 the axis of the links 14 and 14' toward the axis of the legs 9' and 10'.

Having thus described my invention what I claim and desire by Letters Patent to secure is:

95 1. A scribing instrument having, in combination, a handle, a pair of legs pivotally attached to said handle, a screw-threaded rod adapted to slide in said handle, a pair of links pivotally connected with said rod, said links being also pivoted on said legs, and a nut engaging the threads on said rod and adapted to be operated to move said rod relatively to said handle.

105 2. In a scribing instrument a pair of legs pivotally connected together, a pair of links pivotally connected together, said links being also pivoted upon said legs, a handle mounted upon the pivot for one of said pairs, a screw-threaded rod mounted upon the pivot for the other of said pairs, said rod adapted to slide in said handle, and a nut mounted in said handle and having screw-threaded engagement with said rod and adapted to be operated to move said 110 pivots toward and away from each other whereby the legs of said scribing instrument may be moved relatively to each other.

115 3. A scribing instrument having, in combination, a pair of legs pivotally connected together at their upper ends, a centering member pivotally mounted upon the free end of one of said legs, a scribing member pivotally mounted upon the free end of the other of said legs, a pair of links pivotally connected together at their upper ends, means to slidably connect the free ends of one of said links to said centering member, and means to slidably connect the free end of the other of said links to said scribing 120 125 130 member.

- member, said links also being pivoted substantially midway of their lengths to said legs.
4. A scribing instrument having, in combination, a pair of bifurcated legs pivotally connected together at their upper ends, a link pivoted between the furcations of each of said legs, the upper ends of said links being pivotally connected together, a centering member detachably pivoted upon the free end of one of said legs and slidably attached to the free end of the link pivoted on said leg, a scribing member detachably pivoted upon the free end of the other leg of said instrument and slidably attached to the free end of the link pivoted on said last named leg, and means adapted to clamp said centering and said scribing members to their respective links.
5. A scribing instrument having, in combination, a pair of bifurcated legs pivotally connected together at their upper ends, a link pivoted between the furcations of each of said legs, the upper ends of said links being pivotally connected together, a centering member detachably pivoted upon the free end of one of said legs and slidably attached to the free end of the link pivoted on said leg, a scribing member detachably pivoted upon the free end of the other leg of said instrument and slidably attached to the free end of the link pivoted on said last named leg, and means adapted to clamp said centering and said scribing members to their respective links.
6. A scribing instrument having, in combination, a pair of bifurcated legs pivotally connected together at their upper ends, a link pivoted between the furcations of each of said legs, the upper ends of said links being pivotally connected together, a centering member detachably pivoted upon the free end of one of said legs and slidably attached to the free end of the link pivoted on said leg, a scribing member detachably pivoted upon the free end of the other leg of said instrument and slidably attached to the free end of the link pivoted on said last named leg, and means adapted to clamp said centering and said scribing members to their respective links.
7. A scribing instrument having, in combination, a pair of bifurcated legs pivotally connected together at their upper ends, a link pivoted between the furcations of each of said legs, the upper ends of said links being pivotally connected together, a centering member detachably pivoted upon the free end of one of said legs and slidably attached to the free end of the link pivoted on said leg, a scribing member detachably pivoted upon the free end of the other leg of said instrument and slidably attached to the free end of the link pivoted on said last named leg, and means adapted to clamp said centering and said scribing members to their respective links.
8. A scribing instrument having, in combination, a pair of bifurcated legs pivotally connected together at their upper ends, a link pivoted between the furcations of each of said legs, the upper ends of said links being pivotally connected together, a centering member pivotally connected to the free end of one of said legs at a point substantially midway of the ends of said centering member, said member also having a slot extending substantially from said pivot to one end of said member, means arranged adjacent the free end of the link pivoted upon said last named leg adapted to slidably engage said centering member within said slot, a scribing member pivoted at a point substantially midway of its ends to the free end of the other leg of said instrument, said scribing member also having a slot extending substantially from said pivot to one end of said scribing member, and means arranged adjacent the free end of the link pivoted upon said last named leg adapted to slidably engage said scribing member within said slot.
9. A scribing instrument having, in combination, a pair of bifurcated legs pivotally connected together at their upper ends, a link pivoted between the furcations of each of said legs, the upper ends of said links being pivotally connected together, a centering member detachably pivoted to the free end of one of said legs at a point substantially midway of the ends of said centering member, said centering member also having a slot extending substantially from said pivot to one end of said member, said slot having an opening at one side thereof, a screw arranged adjacent the free end of the link pivoted upon said last named leg, said screw adapted to slidably engage said centering member within said slot and to be disengaged therefrom through said opening, a scribing member detachably pivoted at a point substantially midway of its end to the

free end of the other leg of said instrument, said scribing member also having a slot extending substantially from said pivot to one end thereof and provided with an opening at one side of said slot, a screw arranged adjacent the free end of the link pivoted upon said last named leg adapted to slidably engage said scribing member within said slot and be disengaged therefrom 10 through said opening, and means on said

screws adapted to be operated to secure said links to their respective members at predetermined points in said slots.

In testimony whereof I have hereunto set my hand in presence of two subscribing 15 witnesses.

PAUL L. CHARBONNIER.
